UNITED STATES PATENT OFFICE.

EDWARD N. JOHNSTON, OF THE UNITED STATES ARMY.

CONVEYING APPARATUS.

No. 919,178.

Specification of Letters Patent.

Patented April 20, 1909.

Application filed May 6, 1908. Serial No. 431,175.

To all whom it may concern:

Be it known that I, EDWARD N. JOHNSTON, captain of engineers U. S. Army, a citizen of the United States, residing at West 5 Point, in the county of Orange and State of New York, have invented certain new and useful Improvements in Conveying Apparatus; and I do hereby declare the following to be a full, clear, and exact description of 10 the invention, such as will enable others skilled in the art to which it appertains to make and use the same.

My invention relates to improvements in conveying apparatus, and the object of my 15 invention is to provide such apparatus with a means by which it may be controlled from any point that at the time may be found most convenient, as will appear more fully hereinafter.

20 Conveying apparatus, as at present constructed, is sometimes controlled by a man from a switch-board located at the motors, and sometimes by a controller operated by a man on the carriage. In either case, however, 25 it often happens that the operator having the motors under his control is unable to know just where the load should be delivered, and therefore it becomes necessary to station an extra man at a more advanced 30 tageous point, and have him signal such operator and thereby inform him of just what is necessary in order to deliver the load at the exact point desired.

More specifically stated, the object of my 35 invention is to avoid the expense and delay incident to the above objections, and to these ends my invention consists in providing conveying apparatus of all kinds with a movable controller independent of the carriage, 40 which may be located at any desired point, and from which the motors may be operated at will, all as will be more fully hereinafter disclosed, and particularly pointed out in the claims.

45 Referring to the accompanying drawings forming a part of this specification, in which like numerals refer to like parts in all the views, and in which an aerial cableway is shown by way of illustration:—Figure 1, is 50 a sectional view of a stream showing a conveying apparatus stretched thereover; and my controller located at the point to which the material is being delivered, with its cable passing under the water. Fig. 2, is a 55 like view of a river with an island in the middle, showing my controller on said

island, and its cable suspended from a separate wire stretched over the water. Fig. 3, 60 is a sectional view of a canal prism showing my controller located near the point of dropping the load. Fig. 4, is a detail elevational view of one end of a conveyer. Fig. 5, an elevational detail view of my controller and its transporting frame, and Fig. 6, a plan view of the same.

1, represents the towers or other supports on which the track for the conveyer is supported; 2, the track itself; 3, the motor or motors for operating the carriage 4; 5, the connections between the carriage and motors; and 6, the load, all as is well known. As above stated, it often happens that a certain place constitutes a more convenient point from which the motors may be controlled while doing one piece of work, and 70 an entirely different location is far more convenient for another piece of work. In fact, in order that the highest efficiency be attained, it is essential that the controller 7 for the motors 3 be located at such a point 75 that the man in charge of the same can personally superintend and watch the placing of the load 6, on the exact spot where it is to be left. In other words, the controller itself should be placed near, or slightly to 80 one side of such spot, so that the man operating it may be able to personally control the last and final adjustments of the motions of the load before it is detached from the carriage 4. In order to accomplish these 85 most desirable results, it is evident that the controller 7 must be readily movable from place to place, without in the least interfering with the operation of the motors, and therefore I provide a frame 8 for said controller, and mount thereon a drum 10, carrying the cable 11, at all times connected with the motors 3. 9, 9, are supports on which men may stand while operating the controller through the lever 12, and the drum 100 through the lever 13.

The upper portion of the frame 8 is provided with the suspending means 14, by which it may be readily attached to and detached from the hook 15 of the carriage 4, 105 and thereby picked up and put down at any desired point, while the motors themselves furnish the power. Or the frame 8 may be bodily lifted by hand or other power and moved to the desired point of vantage.

110 While being moved by the carriage 4, two men may stand upon the supports 9,

one at each end of the frame, and while thereby balancing the same, one may operate the controller to move the frame to the desired point, while the other winds up or 5 unwinds the drum as may be necessary to give the proper length of cable. In moving from place to place by means of power in this manner, it is often exceedingly convenient to carry a load along at the same 10 time, which load may serve as a temporary foundation for the frame when placed, or for other convenient purposes, and to this end I have left a space 16 in the floor between the controller and drum, in order 15 that the men on the supports 9 may look therethrough, and be able to see just where the load should be dropped. And I have also provided the frame with rods 17 and a hook 18 for supporting this load, as 20 shown.

19, represents a suitable switch board of the relay type provided with suitable solenoids or other devices for making and changing the connections, to which the multiple conductor cable 11 leads from the 25 drum and controller, and from which suitable wires lead to the motors, all as is well known.

The operation of my device is as follows:—When concrete or other material is 30 to be delivered in the middle of a stream, as illustrated in Fig. 1, for example, the controller may be suitably supported on the form, or frame work of the concrete pits, 35 and the cable sunk beneath the water out of the way of all passing craft. Or if, as in Fig. 2, construction work is being carried on within a coffer-dam in the middle of a river, or on an island in the river, the 40 cable may be disposed of as in the previous figure, or it may be supported on a small auxiliary cable stretching from tower to tower. In excavating a canal, as shown in Fig. 3, the cable may follow the contour 45 of the ground. In all of these cases, it is evident that unless the controller be placed at such a point that the operator can see the load when placed, much valuable time and money are of necessity lost, and the 50 work in the end in some cases is not so satisfactory. On the other hand, by selecting the best position for the controller and by moving the same from place to place, if necessary as the work progresses, I am enabled to 55 do away with the signal-man, now commonly employed, and to have the man in charge of the controller itself personally superintend the placing of the material.

Of course I do not desire to be understood 60 as limiting my invention to the exact details of construction above disclosed, for it is evident that the same may be widely varied without departing from the spirit of my invention.

65 What I claim is:—

1. In conveying apparatus, the combination of a conveyer carriage adapted to support a load; a suitable track on which said carriage travels; a motor; connections between said carriage and motor; a controller 70 for said motor and independent of said carriage; and means on said controller whereby it may be carried from place to place, substantially as described.

2. In conveying apparatus, the combination of a conveyer carriage; a suitable track on which said carriage travels; an electric motor; ropes connecting said motor and carriage; an electric controller for said motor, independent of said carriage and adapted to 80 be moved from place to place; and means for readily attaching and detaching said controller from said carriage, substantially as described.

3. In a conveying apparatus, the combination of a conveyer carriage; an aerial rope way on which said carriage travels; electric motors; suitable rope connections between said motors and said carriage; a readily movable electric controller for said motors; 90 a frame independent of said carriage for supporting said controller; and means on said frame for readily attaching and detaching the same from said carriage, substantially as described. 95

4. In a conveying apparatus, the combination of a conveyer carriage; an aerial rope way on which said carriage travels; electric motors; rope connections between said motors and said carriage; a frame independent 100 of said carriage and provided with a support at each end adapted to receive a man; and an electric controller on said support, substantially as described.

5. In a conveying apparatus, the combination of a conveyer carriage; an aerial rope way on which said carriage travels; electric motors; rope connections between said motors and said carriage; a frame independent 105 of said carriage and provided with a support at each end adapted to receive a man; an electric controller and a cable on said support; and means whereby said frame may be readily attached to and detached from said carriage, substantially as described. 115

6. In a conveying apparatus, the combination of a conveyer carriage; an aerial rope way on which said carriage travels; electric motors; rope connections between said motors and said carriage; a frame independent 120 of said carriage and provided with a support at each end adapted to receive a man; an electric controller and a cable drum on said support; means for carrying a load from said frame; and additional means whereby 125 said frame may be readily attached to and detached from said carriage, substantially as described.

7. In a conveying apparatus, the combination of a conveyer carriage; a suitable way 130

on which the same travels; suitable motors and connections by which said carriage is caused to traverse said way; a readily movable controller independent of said carriage 5 adapted to be placed at any desired point of vantage; a frame provided with a support open at its center for said controller; means on said frame from which a load may be suspended; and additional means whereby the 10 same may be readily transported to and left at any desired point, substantially as described.

8. In a conveying apparatus, the combination of a conveyer carriage adapted to support a load; a suitable track on which said carriage travels; a motor; connections between said carriage and motor; a controller for said motor and independent of said carriage; and means on said controller whereby 20 it may be carried from place to place and constantly maintained in operative connection with the motor.

9. In a conveying apparatus, the combination of a conveyer carriage; a suitable track 25 on which said carriage travels, an electric motor; ropes connecting the motor and carriage; an electric controller for said motor, independent of said carriage and adapted to be moved from place to place and constantly 30 maintained in operative connection with the

motor; and means for readily attaching and detaching said controller from said carriage.

10. In a conveying apparatus, the combination of a conveyer carriage; an aerial rope way on which said carriage travels; electric 35 motors; suitable rope connections between said motors and said carriage; a readily removable electric controller for said motors adapted to be constantly maintained in operative connection therewith; a frame independent 40 of said carriage for supporting said controller; and means on said frame for readily attaching and detaching the same from said carriage.

11. In a conveying apparatus, the combination of a conveyer carriage adapted to support a load; a suitable track on which said carriage travels; a motor; connections between said carriage and motor; a controller for said motor independent of said carriage adapted to be moved from place to place, and a flexible connection between the controller and motor whereby they are maintained constantly operatively associated.

In testimony whereof, I affix my signature, 55
in presence of two witnesses.

EDWARD N. JOHNSTON.
